UNITED STATES PATENT OFFICE

163,393

DISPENSER FOR FLUID SUBSTANCES

Joseph Korotkin, New York, N. Y.

Application January 19, 1951, Serial No. 13,880

Term of patent 7 years

(Cl. D52—2)

To all whom it may concern:

Be it known that I, Joseph Korotkin, a citizen of no country, residing in New York city, county of New York, and State of New York, have invented a new, original, and ornamental Design for a Dispenser for Fluid Substances, of which the following is a specification, reference being had to the accompanying drawing, forming part thereof, wherein,

Figure 1 is a front elevational view of a dispenser for fluid substances, showing my new design.

Figure 2 is a side elevational view.

Figure 3 is a rear elevational view, and

Figure 4 is a top plan view of the dispenser shown in Figures 1, 2, and 3 with the cover removed.

I claim:

The ornamental design for a dispenser for fluid substances, substantially as shown.

JOSEPH KOROTKIN.
